UNITED STATES PATENT OFFICE.

FRANK A. RADEMACHER, OF FORKS, NEW YORK.

WRENCH.

969,189.

Specification of Letters Patent. Patented Sept. 6, 1910.

Application filed January 12, 1910. Serial No. 537,749.

To all whom it may concern:

Be it known that I, FRANK A. RADEMACHER, a citizen of the United States, residing at Forks, in the county of Erie and State of New York, have invented a new and useful Improvement in Wrenches, of which the following is a specification.

This invention relates to a wrench which is more particularly designed for turning pipes although the same may also be used for turning screw nuts and other purposes.

The object of this invention is the production of a wrench of this character which is simple and durable in construction and which permits a firm grip to be obtained on the article to be held with the application of a small amount of power.

In the accompanying drawings: Figure 1 is a side elevation of my improved wrench. Fig. 2 is a top plan view thereof.

Similar letters of reference indicate corresponding parts in both figures.

In its general organization my improved wrench resembles a pair of tongs and comprises a pair of hand levers A, B which cross each other near their front ends and are adapted to be grasped at their rear ends by the hand of the operator. At its front end the hand lever B is provided with a front jaw c which projects laterally toward the front side of the wrench and which has a gripping face c¹ arranged substantially at right angles to the longitudinal rear part of this lever, said gripping face being on the rear side of the jaw c. At the base of the jaw c the lever B is provided with an off-set portion d which projects laterally toward the rear side of the wrench and which forms a recess or pocket d¹ on the front longitudinal side of this portion of the lever B. The other hand lever A is provided at its front end with a jaw e which projects laterally toward the front side of the wrench and has a gripping face e¹ arranged at an oblique angle to this hand lever and turned toward the front end of the wrench so as to stand opposite the face of the front jaw c. The faces of the jaw may be either plain or toothed but as shown in the drawings the front jaw is plain while the rear jaw is toothed. In rear of its jaw e the hand lever A is provided with an off-set portion f which projects laterally toward the front side of the wrench thereby forming a pocket or recess f¹ on the rear longitudinal side of this lever.

The two hand levers A, B are pivotally connected by means of a link G which is arranged obliquely across the front ends of the levers and preferably consists of two sections G arranged on opposite sides of the front ends of the hand levers. At one end this link is pivoted to the lever B at the front end of its off-set portion by means of a transverse rivet h, as shown, or any other suitable connection while the opposite end thereof is pivoted to the front end of the other lever A by means of a transverse bolt i, as shown, or other approved connection.

When using the wrench the rear ends of its hand levers are swung apart thereby separating the jaws of the same and permitting of introducing the pipe or other article to be gripped into the mouth of the wrench. Upon pressing the rear ends of the hand levers together the front and rear jaw and the link G adapt themselves to the outer surface of the pipe and grip the same at three different points of its periphery and at the same time press the pipe into the V-shaped spaces between the link and the front and rear jaws, whereby a powerful hold is obtained on the pipe and the same is compelled to turn with the wrench. In order to permit of adjusting the wrench so as to adapt the same to articles varying greatly in size the link G is provided with a longitudinal row of openings j and the off-set part of the hand lever A is provided with a curved row of openings k into one or the other of which the bolt i may be shifted to suit the size of the pipe, nut or other article to be grasped and turned.

By off-setting the hand lever B adjacent to the rear jaw a space is provided which receives the article to be grasped and permits the wrench to properly embrace said article and obtain an effective grip thereon.

The off-set in the lever A permits of arranging the openings k in a curved line 100 which permits of more readily adapting the wrench to articles varying largely in size and still cause this part of the hand lever A to be of substantially the same width as the adjacent parts of this hand lever.

I claim as my invention:

1. A wrench comprising a pair of hand levers which cross each other but are disconnected at the crossing between the same, one of said levers being provided at its front end with a front jaw and the other lever being provided at its front end with a rear jaw

which opposes the front jaw, and a link connected by fixed pivots with said levers in rear of said jaws.

2. A wrench comprising a pair of hand levers which cross each other but are disconnected at the crossing between the same, one of said levers being provided at its front end with a front jaw and the other lever being provided at its front end with 5 a rear jaw which opposes the front jaw and a link connected by fixed pivots with said levers between their jaws and the crossing thereof.
3. A wrench comprising a pair of hand levers which cross each other but are disconnected at the crossing between the same, one of said levers having a front jaw at its front end and an outwardly off-set portion adjacent to said jaw, and the other lever 10 having a rear jaw at its front end which opposes said front jaw, and a link connected by fixed pivots with said levers in rear of their jaws.

4. A wrench comprising a pair of hand levers which cross each other, one of said levers having a front jaw at its front end and an outwardly off-set portion adjacent to said jaw, and the other lever having a rear jaw at its front end which opposes said front jaw and an outwardly off-set portion adjacent to said rear jaw, and a link connecting the off-set portions of said levers. 25

5. A wrench comprising a pair of hand levers which cross each other but are disconnected at the crossing between the same, one of said levers having a front jaw and the other a rear jaw, and a link connected 30 by fixed pivots with said levers and composed of two sections arranged on opposite sides of the levers. 35

Witness my hand this 21st day of December, 1909.

FRANK A. RADEMACHER.
